CANDLE MAKING MACHINE

George Spiros Flomp, San Jose, Calif.

Application May 24, 1954, Serial No. 431,837

5 Claims. (Cl. 18—24)

This invention relates to the art of making candles and more particularly to certain novel improvements in candle making machines.

In the art of making candles it has been the practice to mechanize the process of dipping with the purpose of simulating the steps in the hand dipping of candles. As of old, a wick is periodically dipped into molten wax and withdrawn therefrom with a layer of wax deposited thereon for cooling to a predetermined temperature. This dipping process is continued so as to collect coat upon coat of wax until the candle has developed into a taper or candle of the diameter desired. In this process it is very important that each coat of wax deposited upon a prior one be welded and merged into one homogeneous body of wax. Otherwise each coating of wax would become stratified and be likely to break away from the preceding coats of wax.

It will therefore be understood that in the art of candle making the timing between each immersion as well as atmospheric and temperature conditions between immersions are critically important to the production of a sound, uniform and well constructed candle. These facts are fundamental whether the candles are hand made or machine dipped, but must be reconciled with in the manufacture of candles in machines.

More particularly, in the making of candles in a machine it is usually the purpose to mass produce, i. e., to make great quantities of candles simultaneously. This necessitates the suspension or stringing of the wicks in groups that will fit into the vat containing the molten wax which of course requires that the wicks in each group thereof be in close proximity to each other leaving enough space between them to accommodate the girth of the individual candles and yet leave sufficient clearance between them to facilitate the cooling of the wax between each dipping operation.

In addition to the foregoing, it is equally important to allow sufficient cooling time between each dipping operation so that the last applied coat of wax will not melt away during the next or successive dipping operations. With these fundamental requirements in mind, it is an object of this invention to provide a candle making machine in which candles simulating hand made candles can be mass produced.

Another object of this invention is to provide a machine in which groups of candle wicks strung on a frame can be placed on a conveyor for periodic dipping and intermittent cooling in timed relation. In this connection it is a further object to provide wick holding frames readily attachable to an automatic conveyor-dipper so that new groups of wick holding frames can replace those on which candles are already formed without stopping the intermittently operated conveyor-dipper.

Yet another object of this invention is to provide a conveyor for supporting a plurality of groups of candle wicks strung on frames for intermittent movement toward a dipping station. In this connection, it is an object to

2

provide a dipping station in which each group of candle wicks on a frame upon arrival at such station automatically sets the latter in motion for dipping the frame into molten wax for a predetermined time after which such frame is automatically raised and again assumes its position in the conveyor for intermittent movement thereby.

Another object is to provide a candle making machine for conveying independent groups or racks of candle wicks intermittently to a dipping station, dipping each such group 10 while other groups are maintained in line for successive positioning at such dipping station and subject to removal from such line and replaceable by a new group or rack without interfering with the intermittent operation of the machine.

15 These and other objects and advantages of the present invention will become apparent from a reading of the following description in the light of the drawings in which:

Fig. 1 is a side elevation partly in section and broken 20 away to illustrate the general assembly of a candle making machine embodying the present invention.

Fig. 2 is a fragmentary horizontal section taken along line 2—2 in Fig. 1.

Fig. 3 is a horizontal plan view taken from above in 25 Fig. 1 and substantially along line 3—3 thereof.

Fig. 4 is a fragmentary horizontal section through the machine shown in Fig. 1 and taken substantially along line 4—4 thereof.

Fig. 5 is a plan view of the drive mechanism of Fig. 1.

30 Fig. 6 is a schematic diagram of the control system and mechanisms associated with the dipping station shown at the right in Fig. 1.

Fig. 7 is a perspective view of one of the frames on which wicks are strung and constituting one group thereof.

35 Referring to Fig. 1, the candle making machine of the present invention, designated 10, generally comprises a conveyor 11 connected to a drive 12 for moving a plurality of groups of candle wicks 13 through a circuitous path to and from a dipping station 14 for periodic dipping 40 into a vat of molten wax 15 under the control of an automatically operated control 16.

The conveyor 11, for the purposes of the present invention, is mounted for rotation about a fixed shaft or mast M. The conveyor preferably includes a tubular 45 shaft 20 mounted for rotation on the fixed mast and coupled to the drive 12. The conveyor has a plurality of elevator guide shafts 21 supported for up and down movement relative to an annular frame 22 carried by the tubular shaft 20.

50 The frame 22 consists of a plurality of arms 23 extending radially from a hub 24 secured to the shaft 20 at the desired elevation. These radially extending arms 23 are further supported by straps 25 each of which has one of its ends secured to a flange 26 mounted on top of the tubular shaft 20 and its opposite end secured as at 27 to a respective one of the radial arms 23 for supporting the latter at right angles to the mast. Each of the radial arms 23 are further supported in equally spaced relation by an annular band 28 connected to each of these arms 55 23 adjacent their outer extremity, i. e., between the latter and the point of connection 27 between each arm and the diagonal strap 25.

The extremity of each arm 23 is provided with a guide 60 sleeve 29 having its guide passage 30 disposed vertical to receive one of the elevator guide shafts 21 hereinbefore mentioned. Each of the guide shafts 21 is identical and therefore like reference numerals will identify like parts thereof. Each guide shaft 21 has a tapered lower end 31 (Fig. 7) with a diametrical bore 32 for receiving a pin or bolt 33. Just above the tapered lower end 31 is a cone like collar 34 (Figs. 1 and 6) having its

base or flat side 35 down and its bevel side up. The flat base 35 of the cone collar 34 engages a latch lever 36 which is pivotally supported as at 37 on an extended portion 38 of the radial arm 23. This latch lever 36 is urged outwardly away from the guide sleeve 29 by a compression spring 39 so as to maintain the lower notched end of the latch lever 36 in keeping engagement with the cone shaped collar 34. The latch lever 36 has an outwardly extending dog leg 40 which when pressed inwardly against the action of the spring 39 causes the lower notched end of the lever to disengage its keeping relation with respect to the cone collar 34.

The upper end of each guide shaft 21 is provided with an enlarged disc like head 41 part of which over rides an outwardly extending flange or shelf 42 formed as a part of a fixed track 43. This fixed track 43 is supported on the upper end of the fixed mast M by spokes 44 extending radially from the mast M and having their outer ends welded to the inner wall of an annular beam 45 from which the flange 42 extends.

The fixed track 43 is continuous excepting at the dipping station 14 where the flange 42 is cut away (Fig. 2) to release the enlarged disc head 41 from normal support by the track at this station. However, at this point in the track 43 is disposed on open ended channel track 53 to receive the enlarged disc head 41 as it moves from and to the track 43 relative to the dipping station 14. The channel track 53 has a pair of inturned flanges 54 serving to receive and support the enlarged disc head 41 and spaced from each other to clear the guide shaft 21 which is suspended from the disc head 41 to thereby couple the shaft 21 to the track 53.

The channel track 53 has its upper web secured to the lower end of a rod 55 having its upper end connected to a piston 56 disposed for up and down movement in a cylinder 57 the jacket 58 of which is fixedly supported by lateral brackets 59 extending toward the conveyor 11 from a stationary control panel 60 at the dipping station 14.

The lower portion of the cylinder 57 is in communication with a pipe line 61 in which fluid under pressure is contained. In the present system, compressed air is supplied to the line 61 from a source not shown via a lead-in pipe 62. This lead-in pipe 62 is in communication with a three-way solenoid valve 63 one side 64 of which affords admission of compressed air into the lower end of the cylinder 57 for lifting the piston 56. The three-way solenoid valve 63 includes a third side or relief port 65 by which compressed air is allowed to escape from the lower end of the cylinder 57 so that the piston 56 can drop by gravity when the latch lever 36 on the particular elevator guide shaft 21 connected thereto is released in a manner now to be explained.

As hereinbefore pointed out, each latch arm 36 includes an outwardly extending dog leg 40. Each of these dog legs, in turn, is adapted to be disposed in alignment with an armature 67 of a release solenoid 68 fixedly mounted on the control panel 60 at the dipping station. The coil of this release solenoid 68 is in a circuit 69 controlled by a switch 70 operated automatically upon the arrival of a particular elevator guide shaft 21 at the dipping station. This is clearly illustrated in Figs. 5 and 6 wherein the actuating button 71 of switch 70 is disposed for depression by each point of a star wheel 72 which is secured to the tubular shaft 20.

The tubular shaft 20 as hereinbefore explained is coupled to the drive 12. This is accomplished through a gear 73 secured to the tubular shaft 20 and in mesh with a train of gears 74 drivingly connected to an electric motor 75. This train of gears 74 includes a gear 76 which is driven continuously by the motor 75 and a Geneva drive 77 by which a quarter turn is accomplished once in each half revolution of the gear 76. This quarter turn of the Geneva drive is transmitted via small gears 78-79 to the gear 73 secured to the tubular shaft 20

so as to move the latter along one twelfth of a turn or a fractional distance comparable to the number of elevator guide shafts 21 on the conveyor 11.

It should here be noted that the Geneva drive 77 is so constructed as to block any over-ride of a particular elevator guide shaft 21 past the dipping station 14. In this manner the conveyor 11 is moved and stopped intermittently so that each guide shaft 21 is positioned in succession at the dipping station 14 for a predetermined time. The time lapse afforded by the Geneva drive 77 is sufficient to allow the elevator guide shaft positioned at the dipping station to be lowered and raised once prior to the next intermittent movement of the conveyor 11.

As previously stated, the star wheel 72 is synchronized with the intermittent motion of the conveyor 11 so as to operate the switch 70 upon arrival of each elevator guide shaft 21 at the dipping station 14. In this manner electrical current flows through the circuit 69 to a release timer relay R when in turn completes circuit to the coil of solenoid 68 to effect movement of the armature 67 thereof toward the dog leg 40 on the particular latch arm 36 of the guide shaft 21 so situated. This action is depicted in Fig. 6, showing the arm 36 rocked against the action of its compression spring 39, into a position where its notched lower end disengages the cone collar 34 on the guide rod now positioned at the dipping station 14.

The three-way solenoid 63 previously mentioned is set to normally shut off the admission of air from the supply line 62 and to communicate the lower end of the cylinder 57 with the relief port 65. Consequently upon release of the latch arm 36 from latching engagement with the cone collar 34 on the elevator shaft 21, the latter would be free to fall by gravity. However, since the piston rod 55 must be locked in raised condition to support the channel track 63 in alignment with the fixed track 43, a latch lever 90 is provided on the control panel 60 to engage a roller 91 on a lateral arm 92 secured to the piston rod 55. This latch lever 90 is associated with a solenoid 93 secured to the control panel 60 and operatingly connected to the release timer relay R conjointly with the lead wires going to the release solenoid 68 by which the elevator guide shaft 21 is released. In this manner both solenoids 68 and 93 are energized simultaneously to allow the elevator guide shaft 21 and piston and piston rod 55 to drop by gravity.

It will be noted that the tapered lower end 31 of each elevator guide rod 21 is seated in a socket formed in a boss 80 formed as a part of a frame 81 upon which candle wicks W are strung. This frame 81 may be of any suitable design but I prefer the simplest form as shown in Fig. 7 in which the wicks W are a continuous string mounted in zig-zag fashion on clips 82 punched out of metal straps 83 in the frame 81. The two upper straps are secured to a cross bar 84 to which the boss 80 is welded. The two lower straps are suspended from the respective upper straps by the wick material so as to weigh the wicks down whereby all strands are perfectly vertical during immersion into the molten wax.

With the foregoing in mind it will be apparent that as an elevator guide shaft 21 is released the weight of the frame 81 assists in causing the rod 21 to drop by gravity. Thus, the frame 81 with its group of wicks W is lowered into the vat of molten wax 15.

Referring to Figs. 1 and 6, it will be noted that the particular elevator guide shaft 21 which is lowered, in the manner aforesaid, is now disconnected from the stationary track 43. In other words, the channel track 53 supports the disc head 41 of this singular elevator shaft and the entire arrangement is now under the control of the automatic control mechanism at the dipping station. In this connection note that the piston rod 55 has a collar 85 formed thereon just above its point of connection with the channel track 53. This collar 85 carries the lateral arm 92 on which the roller 91 is mounted. The free end of the arm 92 serves to operate switches 87 and 88 at the

upper and lower limits of movement of the elevator guide shaft 21. These switches 87 and 88 are fixedly mounted on the stationary control panel 60 and have their actuating levers in the path of movement of the lateral arm 92 for the purpose explained. However, it should be noted that the upper switch 87 is normally closed and the lower switch 88 is normally open. Consequently, when the arm 92 drops with the released elevator guide shaft the upper switch 87 assumes circuit making condition for reasons later to become apparent.

Now, when the particular elevator guide shaft 21 of which is at the dipping station reaches its lowermost extremity of movement, i. e., when the candle wick frame 81 associated therewith is immersed in the molten wax, the lateral arm 92 strikes the actuating lever on the lowermost switch 88 which completes the electrical circuit 69 to a timer relay 94 for establishing a circuit to the coil of the three-way valve solenoid 63 via the normally closed upper switch 87. Thereupon the three-way valve 63 is changed in position to admit compressed air from supply pipe 62 into the lower region of the cylinder 57 via the pipe line 61. Thus the compressed air lifts the piston 56 and with it the guide shaft 21 connected thereto. As the elevator guide shaft 21 rises the lateral arm 92 thereon strikes the actuating lever on the normally closed upper switch 87 whereupon the circuit to the coil of the three-way valve solenoid 63 is broken to allow the three-way valve to return to normally closed condition. In this manner the relief port 65 again becomes communicated with the lower portion of the cylinder 57 to relieve the latter of air pressure. Simultaneous with the foregoing the roller 91 on the lateral arm 92 passes the end of the latch lever 90 which thereupon prevents the lowering of the elevator guide shaft 21 upon relief of compressed air from the cylinder when the three-way valve returns to normal position as just stated above.

The cycle of operation at the control 16 thus being completed the motor 75 having continued to drive the main 76 and with it the Geneva drive 77 so that the latter now makes a quarter turn. This action of the Geneva drive is again transmitted to the small gears 78—79 to move the gear 73 on the tubular shaft 20 another step (i. e., the circumferential distance between the elevator guide shafts 21). Thus the elevator shaft 21 which was previously lowered will again have its disc head 41 supported on the fixed track 43 and the disc head 41 of the next successive elevator guide shaft will now be disposed in the channel track 53 for support thereby.

The foregoing intermittent operation of the conveyor 11 and each elevator guide shaft 21 continues under the automatic control 16 so as to dip each group or rack of candle wicks W into the vat 15 of molten wax. In this manner after each dipping operation each rack or group of wicks is carried around the circuitous path by the conveyor 11 giving the wax coating applied to the wicks a chance to cool and harden sufficiently before again being dipped into the vat of molten wax. With each immersion of the wicks W of each group thereof the additional coats of wax build up upon the previously applied coats thereof in the same manner as heretofore practiced in hand dipping of candles. After the proper number of dippings of the several racks or groups of wicks each such rack can be removed from the machine by withdrawal of the pin 33 from the boss 80 and tapered lower end 31 of the elevator guide shaft 21. A newly strung rack of wicks W is then attached to the elevator guide shaft while other racks are being dipped and the machine 10 thus continues to operate without stopping.

While I have described my improved candle making machine in specific detail it will be understood that the same is susceptible to alterations, variations and/or modifications without departing from the spirit of my invention. I therefore desire to avail myself of all alterations, variations and/or modifications as fairly come within the purview of the appended claims.

What I claim as new and desired to protect by Letters Patent is:

1. In combination with a conveyor for intermittently moving a plurality of groups of candle wicks in succession to and from a dipping station for immersion into a vat of molten wax, wick suspending elevator shafts supported for up and down movement on said conveyor, each having a rider on its upper end, a fixed track adjacent said conveyor engaged by the riders on said shafts to hold the same in raised position, said fixed track having a gap formed therein at said dipping station for releasing said riders as they register therewith, an hydraulic cylinder at said dipping station including a vertically movable piston and piston rod, a channel track secured to the lower end of said piston rod disposed in said gap for receiving and supporting each said rider as it arrives at said dipping station, latch means for holding said piston rod in raised position, a compressed fluid line communicated with said cylinder, a solenoid operated three-way valve in said compressed fluid line, and a control circuit including a release solenoid for said latch means, a switch operatively associated with said conveyor to close circuit to said release solenoid upon the arrival of an elevator shaft at said dipping station, and a limit switch at the end of the stroke of said rod engageable thereby for energizing the solenoid operated three-way valve for raising said piston rod into latched engagement with said latch means.
2. In a candle making machine including a vat of molten wax at a dipping station and a conveyor for intermittently moving a plurality of groups of candle wicks through a circuitous path for stoppage in succession at said dipping station, comprising a plurality of elevator shafts each having a group of candle wicks suspended from its lower end supported in spaced relation on said conveyor for up and down movement relative thereto, and a latch lever for normally latching said shaft in raised position, and control means at said dipping station comprising an hydraulic lift including a piston rod axially aligned with a particular elevator shaft disposed at said dipping station, coupling means on the lower end of said piston rod for coupling the latter to an elevator shaft as the latter moves into register with said dipping station, a switch arranged adjacent said conveyor, detent means on said conveyor coordinated with each of said groups of candle wicks for closing said switch upon arrival of an elevator shaft at said dipping station, a release solenoid energized by said switch for releasing said latch lever relative to said elevator shaft, a conduit for supplying fluid under pressure to said hydraulic lift, a solenoid controlled three-way valve in said conduit normally positioned to block the supply of fluid under pressure to said hydraulic lift and to vent the latter to afford unrestrained movement of said piston rod under the influence of gravity, and a limit switch on said control panel engageable by an elevator shaft lowered with said piston rod for completing circuit to the solenoid of said three-way valve for supplying fluid under pressure to said hydraulic lift for raising said piston rod and said elevator shaft into normal position relative to said conveyor for latching engagement with said latch lever.
3. In a candle making machine having a conveyor for intermittently moving a plurality of groups of candle wicks in succession to and from a dipping station for immersion into a vat of molten wax, a plurality of wick suspending elevator shafts arranged for vertical reciprocation on said conveyor, a latch means on said conveyor for holding each elevator shaft in raised position, an hydraulic cylinder at said dipping station including a vertically movable piston and piston rod, means on the lower end of said piston rod for receiving and supporting each said elevator shaft as it arrives at said dipping station, a compressed fluid line communicated with said cylinder, a solenoid operated valve in said compressed fluid line, and a control circuit including a

release solenoid for said latch means, a switch operatively associated with said conveyor to close circuit to said release solenoid upon the arrival of an elevator shaft at said dipping station and to energize said solenoid operated valve to lower said piston rod, and a limit switch at the end of the stroke of said rod engageable thereby for energizing the solenoid operated valve for raising said piston rod and the elevator shaft supported thereby into a position for latching engagement by said latch means.

4. In a candle making machine for intermittently moving a plurality of groups of candle wicks in succession to and from a dipping station for immersion into a vat of molten wax comprising a fixed track, an intermittent movement conveyor adjacent said track having a plurality of guide sleeves thereon, a wick suspending elevator shaft supported in each said guide sleeve for up and down movement relative thereto, latch means on said conveyor for holding each elevator shaft in raised position, a rider on each said shaft above said fixed track, said fixed track having a gap formed therein at said dipping station for passage of a rider downwardly, an hydraulic cylinder at said dipping station including a vertically movable piston and a piston rod having a channel track secured to its lower end disposed in said gap for receiving and supporting each rider as it arrives at said dipping station, a compressed fluid line communicated with said cylinder, a solenoid operated valve in said compressed fluid line for normally holding said piston rod in raised position, and a control circuit including a release solenoid for said latch means, a switch operatively associated with said conveyor upon the arrival of an elevator shaft at said dipping station to close circuit to said release solenoid to release said elevator shaft from said latch means and to energize said

solenoid operated valve to lower said elevator shaft, and a limit switch at the end of the dipping stroke of said rod engageable thereby for establishing circuit to the solenoid operated three-way valve for operating the latter to raise said piston rod and the elevator shaft supported thereby into latched engagement with said latch means.

5. A candle making machine for intermittently moving a plurality of groups of candle wicks in succession to and from a dipping station for immersion into a vat of molten wax comprising a fixed track, an intermittently movable conveyor adjacent said fixed track, a plurality of candle wick suspending elevator shafts supported in spaced relation along said conveyor for up and down movement relative thereto, track engaging means on each said shaft engageable with said fixed track to support said shaft and the candle wicks suspended therefrom in up position, said fixed track having a gap therein at said dipping station, and supplemental elevating means at said dipping station including a track section disposed in said gap for receiving the track engaging means on said elevator shafts and for supporting each said elevator shaft in register with said gap, and means operable in timed relation with said intermittently movable conveyor for lowering and raising said track section once during each dwell of an elevator shaft at said dipping station.
